UNITED STATES PATENT OFFICE

JAMES ROBERT COE, OF WATERBURY, CONNECTICUT, ASSIGNOR TO THE AMERICAN BRASS COMPANY, OF WATERBURY, CONNECTICUT, A CORPORATION OF CONNECTICUT.

ELECTRIC MELTING FURNACE.

Application filed October 18, 1921. Serial No. 508,448.

The present invention relates to furnaces and has special reference to induction furnaces of the type illustrated and described in the patent to Wyatt No. 1,201,671 dated October 17, 1916.

Induction furnaces of this type are usually provided with a crucible or lined casing for molten metal and an extension forming a channel box, having a lining which is provided with a substantially V-shaped channel having its ends opening into the crucible. The lined extension has a transverse aperture which is located between the legs of the channel and through which the central leg of the transformer that surrounds the extension extends, the transformer primary generating secondary currents in the molten metal within the legs of the channel to heat and cause a flow of the metal within the channel and thus to effect the desired melting and mixing of the metal within the container. The lining of the channel box which constitutes the walls of the channel is made of refractory material which while in a damped powdered or granulated form is rammed into the metal casing of the box so as to be integral with the lining of the container casing and afterwards the moisture in the refractory material is dried out. This manner of constructing the channel lining has been found very difficult and expensive and the drying process is liable to result in cracks and fissures in the channel box lining.

The object of the present invention is to provide a channel box and lining for a furnace of the type above indicated which is less expensive and more perfect in construction than those heretofore produced.

Another object of the invention is to provide a novel and improved furnace of this type.

The several features of the invention will be clearly understood from the following description and accompanying drawings, in which

Figures 1 and 2 are side and front elevations, respectively, of a furnace embodying the features in their preferred form;

Fig. 3 is a horizontal sectional view, partly in elevation, taken on the line 3—3 of Fig. 2;

Fig. 4 is a vertical sectional view, partly

in elevation, taken on the line 4—4 of Fig. 2; and

Fig. 5 is a detail front elevation of a component part of the channel block on a reduced scale.

The furnace illustrated in the drawings is provided with a crucible or container 2, a channel box 4 having a separate lining with a substantially V-shaped channel 6 having its ends opening into the container, and a transformer core 8 having a primary coil 48 arranged to generate secondary electric currents in the molten metal within the legs of the channel as and for the purpose fully described in the patent to Wyatt No. 1,201,671 hereinbefore referred to.

As shown, the container is provided with a vertical cylindrical shell or casing 10 which is closed by top and bottom plates 12 and 14, respectively, secured to the shell by means of angle-irons 16 embracing the shell. The top plate 12 is provided with a charge opening 18 which may be closed by a cover 20 pivoted at 22 on the top plate. The bottom plate is provided with a rectangular opening 24 for a purpose herein-after described. The cylindrical shell 10 is provided with a lining 26 of heat insulating material, and an inner lining of refractory material 27.

In the illustrated construction, the channel box 4 is attached to the container and the component parts of the channel box and its lining are assembled before they are attached to the shell of the container. The channel box is provided with a lining or block 28 which is made in two sections. The sections of the block are separately formed or molded and each is provided with parallel faces. These sections are formed of refractory material and are then dried and baked. A groove 30 is formed in a face of each section having its lower portion V-shaped and its ends extending to the top of the section, as shown in Fig. 5. Each section is provided with a central aperture 32. When the sections are assembled, the grooves 30 register to form the channel 6, and the apertures 32 in the sections also register. The two sections of the block are then assembled, the joint being closed by suitable cement 34 and clamped together by means of plates 36 on their outer faces, which

plates are connected by clamping bolts 38. These bolts extend through the plates, the plates being suitably reinforced by ribs 39. In order to ensure that the plates shall uniformly clamp the faces of the sections throughout their area layers of asbestos felt, plastic cement or other yielding material 41 is placed between the plates and the outer faces of the sections. The plates are provided with apertures which register with the apertures 32 in the sections so that when these parts are assembled a transverse cylindrical aperture 40 is provided in the channel box and its lining. The plates correspond substantially in shape to the faces of the sections but the upper edges of the plates are spaced from the top of the sections and the edges of the lower portions of the plates extend beyond and are arranged parallel with the sides of the lower portion of the sections. The edges of the lower portions of the plates are provided with inwardly projecting ribs or flanges 42 for holding heat insulating material 44 against which the sides of the lower portion of the sections bear.

The transformer is provided with a central leg 46 extending through the aperture 40 in the channel box and encircled by a primary coil 48; and is further provided with outer legs 50 which are by means of adjusting screws 54 supported on brackets 52 projecting laterally from the plates.

To attach the channel box and its lining to the container casing when the parts are thus assembled, the upper end of the channel block is inserted in the rectangular opening 24 in the bottom plate 14 of the container and then the channel box is secured to the container casing by means of bolts 56 extending through the outer ends of the brackets 52 and the lower flanges of horizontal channel irons 58 having their upper flanges secured by rivets 60 to the margin of the bottom plate of the container casing.

The refractory material 27 is then applied to the inner surface of the container and about the sides and faces of the portion of the top of the channel block lining that extends through the opening in the bottom of the container to form the lining for the container and to fill the space between the channel block lining and the wall of the opening being so placed so as to form a close bond where it contacts with the channel block lining sections.

The container is provided with a pouring spout 66 secured to the shell 10 and leading from the interior of the container, a suitable aperture being provided in the insulating lining 26 of the container. The refractory material 27 extends through this aperture so as to be integral with the lining of the spout. In order to insure that secondary electric currents shall not be generated in the clamp-

ing plates 36, the upper ends of the plates are spaced slightly from the bottom of the container casing and the portion of the plates between the aperture 40 and their upper ends is provided with a gap 68 ⁷⁰ (Fig. 2).

It will be apparent from the foregoing that the illustrated furnace is of simple and durable construction, that the parts thereof may be easily constructed and assembled, ⁷⁵ and that the joint between the container and channel block is effectively sealed so that there is no danger of molten metal escaping.

It is advantageous to form and dry the channel lining or block before placing it in the furnace as it may be worked upon more conveniently. Furthermore when made in sections cracks are less liable to form while drying and particularly while being baked to increase their strength than in the forms ⁸⁵ heretofore used, and any surface cracks formed during drying can be readily detected by inspection. It has been found that cracks formed, while in use, usually occur substantially parallel to the front and rear ⁹⁰ faces of the block. By making the block in sections not only are cracked blocks detected, but the clamping of the blocks opposes the tendency of any cracks to open and the molten metal is thereby more effectively prevented from escaping through the joint between the sections or through any cracks ⁹⁵ extending in a plane at all parallel with the joint.

While it is preferred to employ the specific construction and arrangement of parts illustrated and described it is to be understood that this construction and arrangement is not essential except so far as specific in the claims. ¹⁰⁰

What I claim is:

1. A furnace of the class described having, in combination, a container for molten metal, a two-part channel box secured to the container, a lining for said box comprising a plurality of sections of refractory material having in their adjacent inner faces registering surfaces forming a channel whose ends open into said container, said sections lying between the two parts of said channel box, means for holding said two parts together so as to clamp the said sections between them, and yielding material between the outer faces of said sections and the two parts of said box. ¹¹⁰ ¹¹⁵ ¹²⁰

2. A furnace of the class described having, in combination, a container for molten metal, a two-part channel box secured to the container, a lining for said box comprising a plurality of sections of refractory material having in their adjacent inner faces registering surfaces forming a channel whose ends open into said container, said sections lying between the two parts of said channel box, means for holding said two ¹²⁵ ¹³⁰

- parts together so as to clamp the said sections between them, and a heat insulating material supported by said channel box parts and located beneath said sections.
5. A furnace of the class described having, in combination, a container for molten metal, a two-part channel box secured to the container, a lining for said box comprising a plurality of sections of refractory material having in their adjacent inner faces registering surfaces forming a channel whose ends open into said container, said sections lying between the two parts of said channel box, and means for holding said two parts together so as to clamp the said sections between them, the upper ends of said sections extending upward into said container, the lining of said container being in intimate contact with said upper ends.
10. 4. A furnace of the class described having, in combination, a container for molten metal comprising a casing and a lining therefor, a two-part channel box secured to said casing, and a separately formed block having a channel whose ends open into said container, said block being clamped between the two parts of said box, the pressure being at right angles to the plane of said channel.
15. 5. A furnace of the class described having, in combination, a container for molten metal comprising a casing and a lining therefor, a two-part channel box secured to said casing, and a separately formed block having a channel whose ends open into said container, said block being clamped between the two parts of said box and extending into said container so as to be in intimate relation with its lining.
20. 6. A furnace of the class described having, in combination a container for molten metal comprising a casing and a lining therefor, a two-part channel box secured to said casing, a separately formed block having a channel whose ends open into said container, said block being located between and supported by the two parts of said box and extending into said container so as to be in intimate relation with its lining, and a closed magnetic transformer core supported on said channel box parts and surrounding portions thereof, one leg of said transformer passing through said block and said parts, said parts having a gap to prevent the formation of secondary currents therein.
25. 7. A furnace of the class described hav-
- ing, in combination, a container for molten metal comprising a casing and a lining therefor, a channel box secured to said casing, and a refractory block having a channel whose ends open upwardly into said casing and having an opening adapted to receive the transformer core between the upwardly extending portions of said channel, said block being within and supported by said box and extending into the container, so as to be surrounded by and in intimate relation with said lining.
30. 8. A furnace of the class described having, in combination, a container for molten metal comprising a casing and a lining therefor, a two-part channel box secured to said casing, and a separately formed block having a channel whose ends open into said container, said block being clamped between the two parts of said box, the pressure being at right angles to the plane of said channel, and yielding material between the outer faces of said block and the two parts of said box.
35. 9. A furnace of the class described having, in combination, a container for molten metal comprising a casing and a lining therefor, a two-part channel box secured to said casing and provided with inwardly extending projections adjacent to their bottom portions, and a separately formed block having a channel whose ends open into said container, said block being located between the two parts of said box and extending upwardly so as to be surrounded by said lining, and heat insulating material supported by said channel box projections and extending upwardly along the lower portions of said block.
40. 10. A furnace of the class described having, in combination, a container for molten metal comprising a casing and a lining therefor, a two-part channel box secured to said casing, a separately formed block having a channel whose ends open into said container, said block being clamped between the two parts of said box and extending into said container so as to be in intimate relation with its lining, a closed magnetic transformer core supported on said channel box parts and surrounding portions thereof, one leg of said transformer passing through said block and said parts, and means carried by said channel box parts for adjusting the position of said transformer core.
